US00D828161S

(12) **United States Design Patent** (10) **Patent No.:** **US D828,161 S**
(45) **Date of Patent:** **** Sep. 11, 2018**

(54) **FOOD CONTAINER COVER**

(71) Applicant: **ZUME Pizza, Inc.**, Mountain View, CA (US)

(72) Inventors: **Julia Collins**, San Francisco, CA (US); **Casper W. Chiang**, Danville, CA (US); **Chester Wajda**, San Francisco, CA (US)

(73) Assignee: **ZUME, INC.**, Mountain View, CA (US)

(**) Term: **15 Years**

(21) Appl. No.: **29/574,805**

(22) Filed: **Aug. 18, 2016**

(51) LOC (11) Cl. **09-07**

(52) U.S. Cl.

USPC **D9/454; D9/452**

(58) **Field of Classification Search**

USPC D9/414, 416, 424, 425, 426, 428, 430, D9/715, 721, 732, 756, 761; D7/601, D7/602, 701, 703, 707, 708

CPC B65D 81/26; B65D 51/00; B65D 71/00; B65D 33/28; A47J 47/14; B65F 1/0006

See application file for complete search history.

CLAIM

The ornamental design for a food container cover, as shown and described.

DESCRIPTION

FIG. 1 is a top isometric view of a food container cover showing one embodiment of our new design.

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof.

FIG. 8 is a right side elevational view thereof.

FIG. 9 is a top isometric view of a food container cover showing another embodiment of our new design.

FIG. 10 is a bottom isometric view thereof.

FIG. 11 is a top plan view thereof.

FIG. 12 is a bottom plan view thereof.

FIG. 13 is a front elevational view thereof.

FIG. 14 is a rear elevational view thereof.

FIG. 15 is a left side elevational view thereof; and,

FIG. 16 is a right side elevational view thereof.

The broken lines in FIGS. 9-16 depict portions of the food container cover that form no part of the claimed design.
